US00D752097S

(12) **United States Design Patent**
Park et al.

(10) **Patent No.:** US D752,097 S
(45) **Date of Patent:** ** Mar. 22, 2016

(54) **DISPLAY SCREEN OR PORTION THEREOF
WITH GRAPHICAL USER INTERFACE**

(71) Applicant: **Samsung Electronics Co., Ltd.**,
Suwon-si (KR)

(72) Inventors: **Min-Sun Park**, Seoul (KR); **Jiny Kwon**,
Sungnam-Si (KR); **Pill-Kyoung Moon**,
Seoul (KR)

(73) Assignee: **Samsung Electronics Co., Ltd.**,
Suwon-si (KR)

(**) Term: **14 Years**

(21) Appl. No.: **29/459,208**

(22) Filed: **Jun. 27, 2013**

(30) **Foreign Application Priority Data**

Jan. 4, 2013 (KR) 30-2013-0000589

(51) **LOC (10) Cl.** **14-04**

(52) **U.S. Cl.**

USPC **D14/489**

(58) **Field of Classification Search**

USPC D14/485-495

CPC G06F 3/04817; G06F 3/0482

(57) **CLAIM**

The ornamental design for a display screen or portion thereof with graphical user interface, as shown and described.

DESCRIPTION

FIG. 1 is a front view of a display screen or portion thereof with graphical user interface, showing our new design; and, FIG. 2 is a front view thereof, in which a display device in broken lines are provided to illustrate an example environment.

The broken lines are for illustrative purposes only and form no part of the claimed design.

1 Claim, 2 Drawing Sheets

FIG. 1

FIG. 2
